UNITED STATES PATENT OFFICE.

GUSTAV SCHWORETZKY, OF EPLINGEN-ON-THE-NECKAR, GERMANY.

PORTABLE FIRE EXTINGUISHER.

1,415,717.

Specification of Letters Patent.

Patented May 9, 1922.

Application filed December 20, 1921. Serial No. 523,703.

To all whom it may concern:

Be it known that I, GUSTAV SCHWORETZKY, residing at Eplingen-on-the-Neckar, Wurttemberg, Germany, have invented certain new and useful Improvements in Portable Fire Extinguishers, (for which I have filed application in Germany Dec. 18, 1920,) of which the following is a specification.

This invention relates to portable fire extinguishers and consists of a stay bolt which connects the top and the bottom of the shell or container and thus stiffens the whole structure, and which is preferably made tubular so that it may at the same time serve as a receptacle for the pressure medium. In this case it may, for instance, be passed through the bottom of the shell and be screwed into the guide for the push-pin provided in the top of the shell for releasing the pressure medium. Other objects of the invention will appear from the detailed description of the improvement, which consists in the features of construction and combination of parts hereinafter described and claimed.

The accompanying drawing shows one construction of the improved fire-extinguisher by way of example, in longitudinal section.

Referring to the drawing *a* is the shell of the fire-extinguisher and *p* the stay bolt or rod which connects the top and bottom end plates and at the same time serves as a receptacle for the pressure medium. After the liquid for extinguishing the fire has been poured into the shell through the opening *f* in the bottom, which latter is adapted to serve as a funnel, the stay rod or receptacle is introduced through the charging opening *f* and its upper end is screwed tightly into the guide bushing *h* of the sliding release pin *g* provided in the top of the extinguisher. This construction has the advantage that the bolt or receptacle *p* cannot be forcibly ejected from the extinguisher in case it should be unscrewed while the shell is accidentally still under pressure, in as much as the tight seal at the bottom is broken as soon as the unscrewing of the bolt or receptacle commences and all the compressed gas freely escapes around the bolt long before the bolt is entirely released from the guide bushing at the top. A further advantage of

this construction, in which the stay bolt also serves as a receptacle for the pressure producing medium, is that the head *b* of the bolt *p* is always visible from the outside of the shell so that the insertion of the pressure receptacle cannot possibly be accidentally overlooked, as happens sometimes with extinguishers of other constructions.

It will be obvious that the details of construction of this improved extinguisher may be modified in many ways within the limit of the claims without departing from the spirit of the invention or sacrificing any of its advantages and that the construction illustrated must be considered as an example only.

In operation the release pin *g* is actuated to free the pressure medium contained in the hollow body *p* which pressure medium then functions to expel the fire extinguisher fluid contained in the shell *a*. The fire extinguishing fluid is expelled through the discharge pipe adjacent one side of the shell *a*.

What I claim as my invention and desire to secure by United States Letters Patent is:

1. In a portable fire extinguisher, a shell containing the extinguisher liquid, end plates secured to said shell, one of said end plates being formed with a charging opening, a hollow stay bolt inserted through said charging opening for connecting said end plates, means on said stay bolt for sealing said charging opening, said bolt being adapted to confine the pressure medium until the device is operated, and a discharge pipe for the extinguishing liquid.

2. The combination in a portable fire extinguisher of a shell containing the extinguishing liquid, end plates for said shell, a tubular bolt insertable through one of said end plates for connecting said end plates and reinforcing said shell, one of said end plates being formed with a charging opening, means on said bolt for closing said charging opening and a head for said bolt disposed outside one of said end plates, said tubular bolt being adapted to confine the pressure medium until the device is operated and a discharge pipe for the extinguishing liquid.

3. The combination in a portable fire extinguisher of a shell containing the extinguishing liquid, end plates for said shell, a tubular stay bolt for connecting said end

plates, one of said end plates being formed with a charging opening, said stay bolt being insertable in the shell through said last mentioned end plate, a bushing carrying a pressure release means mounted in the other end plate, means formed on said tubular bolt for sealing said charging opening, said

tubular bolt screw-threadedly engaging the bushing of said pressure release pin, said tubular bolt being adapted to retain the pressure medium. 10

In testimony whereof I affix my signature.

GUSTAV SCHWORETZKY.
